UNITED STATES PATENT OFFICE.

GEORGE EDWARD BURT, OF HOWARD, MASSACHUSETTS.

PULLEY.

SPECIFICATION forming part of Letters Patent No. 416,561, dated December 3, 1889.

Application filed March 2, 1889. Serial No. 301,735. (No model.)

To all whom it may concern:

Be it known that I, GEORGE EDWARD BURT, a citizen of the United States, residing at Howard, in the county of Worcester and State of Massachusetts, have invented certain new and useful Improvements in Split Pulleys; and I do hereby declare the following to be a full, clear, and exact description of the invention, such as will enable others skilled in the art to which it appertains to make and use the same.

The invention relates to improvements in split or sectioned pulleys, the objects being to provide a pulley in which the lags are not connected together or to the spokes by glue or nails, but are bound together by metal rods or bars and nuts on the same, in which the parts can be quickly and easily separated for repair or other necessary or desired purpose, which can be quickly secured on shafts of different diameters, in which the danger of explosion by centrifugal force generated by rapid revolution will be avoided, which can be used either in a wet or dry atmosphere without injury, and which can have its face turned off smooth and true without danger of injuring the edge of the turning-tool; and it consists in the construction and novel combination of parts hereinafter described, illustrated in the accompanying drawings, and pointed out in the appended claims.

In the accompanying drawings, Figure 1 is a side view of a pulley embodying the invention. Fig. 2 is a central section of the inner portion thereof at right angles to the compound spoke. Fig. 3 is a section of one-half of the pulley parallel to its sides. Fig. 4 is a detail section on the line $x-x$ of Fig. 2. Fig. 5 represents views of the end lag of a section and the part of the spoke that fits therein. Fig. 6 is a side view of one of the semicircular rods detached with the nuts engaged on its ends. Fig. 7 is an edge view of one of the lags. Fig. 8 is a perspective view of the pulley.

Referring to the drawings by letter, A designates a shaft, and B a pulley fitted thereon and embodying the invention.

The pulley consists of two similar sections, each composed of one-half of the rim and one-half of a longitudinally-divided double or compound spoke C, the sections c of which

have their central parts c' in block form or rectangular and have on their inner flat facing sides the transverse central grooves c², 55 having flat sides that form right angles at the bottoms of the grooves, which serve a purpose hereinafter explained. The end portions of the spoke-sections, which are squared, have on their outer surfaces transverse 60 grooves c³, triangular in cross-section to bind them to the rim, which they enter, the ends of the spoke-sections being flush with the outer surface of the rim.

D D are similar rim-sections, very nearly 65 semicircular, and composed of the transverse lags d, set edge to edge. The end lags d' of each section are provided with transverse ribs d², triangular in cross-section, to fit and bind in the corresponding grooves c³, and d³ designates one or more perforations or passageways extending through each rim-section concentric with its curved faces or surfaces and through corresponding perforations in the adjoining spoke-section. 75

E E are curved rods or wires or steel bars extending through the channels d³ and having their ends threaded outside thereof, and e e are nuts engaging said ends and binding the lags together and to the spoke-sections. 80 Any other equivalent means for connecting the spokes and lags may be used. These rods or bars constitute, as it were, backbones for the pulley. It is evident that by means of said nuts and rods the said parts may be 85 held very securely together, so that the pulley will not explode, but will resist the centrifugal force generated by a very rapid rotation. If desired, the edges of the lags may be provided with transverse meeting grooves 90 e', into which are fitted the keys e² to bind the lags more firmly together.

F F are blocks inserted between the facing ends of the rim-sections, and are, if desired, keyed to the end lags in the same manner as 95 the lags are keyed together. The said blocks are provided with openings f f, registering with the channels d³ and adapted to receive the nuts e and threaded ends of the rods E. The central squared parts of the spoke-sections have, preferably, on their outer longitudinal corners or edges angle-re-enforcing plates G, through openings in which and in the spoke-sections pass the bolts g, the thread-

ed ends of which are engaged by the nuts g' . The angle-plates are provided in their in-standing flanges with rectangular notches g^2 , that register with the ends of the grooves c^2 , and are of equal size thereto. By the said bolts and nuts the whole pulley is bound firmly together and the pulley clamped on the shaft. If desired, the spoke-sections may be connected with bolts on each side of their central parts c' .

H II are angle-wedges, or wedges that are bent at right angles centrally and longitudinally, there being four of said wedges, two on each side of the pulley. The said wedges lie opposite each other in the grooves c^2 and notches g^2 , and are tapered from their outer to their inner ends, those on one side binding upon the shaft A, while those on the opposite side ride upon the former, the beveled or tapered sides of the opposite sets being in contact. The outer ends of said wedges have secured to them, by screws or otherwise, the arms h , to the inner ends of which are secured the oppositely-threaded nuts i , the inner edges of which are curved to fit and ride on the shaft A, that aids in holding them in position.

I is a bolt having a central smooth portion and oppositely-threaded end portions, which threads respectively engage the nuts i .

To secure the pulley in place or to tighten it, a rod i' is inserted in an opening in one of the projecting ends of the bolt I and the latter turned in the proper direction to cause the nuts i to approach each other, thus driving the wedges H farther inward and causing them to bind between the shaft and the sections of the compound spoke C. The opposite rotation of the bolt of course loosens 40 the pulley on the shaft.

I' is a supporting-sleeve surrounding the central smooth part of the bolt I, and with its outstanding tongue i^2 secured to one of the spoke-sections.

45 It is evident from the foregoing that the pulley may be secured upon shafts of different diameters, the distance that the angle-wedges are driven inward varying with the diameter of the shaft. It is also evident 50 from the described construction that the pulley can quickly and easily be mounted on and dismounted from a shaft, and that it can be readily taken apart for any necessary purpose. It can also be tightened or loosened with extreme ease and quickness. As 55 its tread is perfectly free from glue or nails, it cannot easily injure the edge of a turning-tool when re-dressing it.

The rods E, which are of steel and which 60 bind the lags and spokes of the sections together, render it almost impossible for the pulley to explode however rapid its rotation, and, as there is no glue to soften nor no nails to rust and loosen, it is evident that the pulley will work equally well in all kinds of weather.

This pulley is equally practical in wet loca-

tions, where rubber belts only could be used; or, in uncommon dry localities, if the lags shrink, the screw-nuts on the semicircular bars or rods may be readily screwed down, drawing all the lags and firmly bind together spokes and lags. The rods and keys hold the lags so they cannot warp or twist, but always present a uniform surface for the belts to run on in the best position of the timber to give the belts the most drawing power on the pulley. Any desirable number of rods or spokes may be used that the size or width of face of the pulley require. It will be readily seen that a light cheap strong pulley is made fitted for various localities and is weather-proof.

Having described my invention, I claim—

1. A sectioned pulley comprising two equal 85 sections, each composed of one section of a longitudinally-divided spoke and a rim-section, the rim-sections being composed of transverse lags and provided with perforations or passages parallel to their faces that 90 extend through the ends of the spoke-sections, rods extending through said perforations or passages, and nuts engaging the threaded ends of said rods outside the channels, substantially as specified. 95

2. In a sectioned pulley, the combination of the spoke-sections having in their squared end portions the transverse grooves c^3 , the rim-sections composed of the transverse lags A and provided with perforations or passages 100 concentric with their curved faces or surfaces, that also extend through the corresponding spoke-sections, the end lags A', provided with transverse ribs to enter and fit in the corresponding grooves c^3 , the rods extending through the perforations or passages in the rim-sections, and the nuts engaging the threaded ends of said rods outside of said perforations or passages, substantially as specified. 110

3. In a pulley, the combination of the equal sections, each composed of the spoke-section c , the lags A, fitted together at their edges and provided with meeting grooves e' in said edges, the keys e^2 , fitted in said meeting 115 grooves, the rods E, extending through the perforations or passages in the rim-section and corresponding spoke-section, and the nuts engaging the threaded ends of said rods outside of said channels, substantially as 120 specified.

4. In a diametrically-sectioned pulley, the combination of the longitudinally-divided spoke, the lags forming the rims of the sections, the rods extending through perforations or passages in the rims and adjacent 125 spoke-sections, the nuts engaging the threaded ends of said rods outside of said channels, the blocks between the rim-sections provided with openings to receive said ends 130 and nuts, and the bolts passing through registering openings in the two spoke-sections and binding the two pulley-sections together, substantially as specified.

5. The combination, with the rim and the longitudinally-divided spoke C, having the opposite central grooves c^2 in its facing sides, which grooves are right-angled at the bottoms, of the binding angle-wedges resting in said grooves and binding on the shaft, and means, substantially as described, whereby the two sets of wedges may be simultaneously forced inward or outward, substantially as specified.
6. The combination, with the rim, the longitudinally-divided compound spoke C, provided with the central transverse grooves c^2 , and the bolts holding the spoke-sections together, of the angle-wedges arranged in two opposite sets, the arms h , attached to the wedges, the oppositely-threaded nuts i , attached to the arms, and the bolt I, engaging said nuts, substantially as specified.
7. The combination, with the rim, the longitudinally-divided spoke C, provided with the grooves c^2 , and the bolts holding the spoke-sections together, of the angle-wedges, the arms h , the oppositely-threaded nuts i , the bolt I, and the supporting-sleeve I', with its

outwardly-extending tongue secured to one of the spoke-sections, substantially as specified.

8. In a pulley, the combination of the perforated lags fitted together, the semicircular rigid rods threaded at their ends, and the nuts engaging on said ends outside of the lags, binding the lags together and holding them in position, substantially as specified.

9. In a diametrically-sectioned pulley, the combination of the semicircular rigid rods threaded at their ends, the lags fitted edge-wise together, the spoke-sections, the spoke-sections and lags having registering perforations for the reception of the said rods, the nuts engaging the ends of the rods, and the bolts binding the two spoke-sections together, substantially as specified.

In testimony whereof I affix my signature in presence of two witnesses.

Correction in Letters Patent No. 416,561.

It is hereby certified that the residence of the patentee in Letters Patent No. 416,561, granted December 3, 1889, upon the application of George Edward Burt, for an improvement in "Pulleys," was erroneously written and printed "Howard, Massachusetts;" that said residence should have been written and printed *Harvard, Massachusetts*; and that the said Letters Patent should be read with this correction therein that the same may conform to the record of the case in the Patent Office.

Signed, countersigned and sealed this 11th day of February, A. D. 1890.

[SEAL.]

CYRUS BUSSEY,

Assistant Secretary of the Interior.
